UNITED STATES PATENT OFFICE.

THEODORE BIRKENMAIER, OF ST. LOUIS, MISSOURI.

WATER-CONTROLLING MECHANISM FOR LAUNDRY-TUBS.

1,252,079.

Specification of Letters Patent.

Patented Jan. 1, 1918.

Application filed May 15, 1916. Serial No. 97,734.

To all whom it may concern:

Be it known that I, THEODORE BIRKENMAIER, a citizen of the United States, residing at St. Louis, in the State of Missouri, 5 have invented a certain new and useful Improvement in Water-Controlling Mechanism for Laundry-Tubs, of which the following is a specification.

This invention relates to fluid controlling mechanisms, and more particularly, to mechanism for controlling the water to be delivered to laundry tubs.

This class of mechanisms operates under unusual conditions, for the reason that the 15 presence of water, soap and lint will seriously affect and hinder the operation of any mechanism which is placed contiguous to a laundry tub, which is subjected to these substances. Moreover, the class of operators 20 employed is usually unskilled, and, therefore, unfamiliar with mechanism and the care required to maintain the same in order.

In some prior constructions, it has been the practice to operate and control the valves 25 by means of springs or electro-magnets. Where a spring is employed, the same is necessarily exposed to the water and soap, and, in a short time, will rust and get out of order, so as to fail to operate the mechanism 30 when desired. An electro-magnet, on the other hand, is liable to become short circuited, or its connections, even though waterproofed, may become short circuited, so as to render the same useless to operate the 35 mechanism. Moreover, an electro-magnet is a rather expensive construction and in addition requires close adjustment to keep it in order.

One of the objects of this invention, therefore, 40 is to provide a fluid controlling mechanism of the class described, in which the operation of the valves will be positive and certain, which is not liable to get out of order, and which is simple in construction and operation, and cheap to manufacture.

Another object is to improve the controlling mechanism, and more especially the valves, as to their details of construction.

Further objects will appear from the detail description taken in connection with the accompanying drawings, in which:

Figure 1 is an end elevation of a laundry

tub showing a controlling mechanism embodying this invention;

Fig. 2 is an enlarged section on the line 55 2—2, Fig. 1;

Fig. 3 is a section on the line 3—3, Fig. 2;

Fig. 4 is an enlarged section on the line 4—4, Fig. 3;

Fig. 5 is an enlarged section on the line 60 5—5, Fig. 3;

Fig. 6 is an enlarged section on the line 6—6, Fig. 3; and

Fig. 7 is an enlarged section on the line 65 7—7, Fig. 2.

Referring to the accompanying drawings, 1 designates a laundry tub having the usual inlet pipe 2, which has a connection at 3 with a pair of valve casings 4, in turn connected with a pair of pipes 5 delivering, respectively, hot and cold water to the valve casings. 70

One of the valve casings is shown in detail in Fig. 5 and as shown it is provided with a removable valve seat 6 coöperating with an 75 outwardly opening valve 7 having a stem 8 guided in a bearing 9 on the valve seat. The valve seat extends downwardly to form a short cylinder 10, one of whose heads 11 is provided with a number of small perforations 12, and whose other head 13 is removable. Both heads are machined to provide bearings for the valve stem. This valve stem has fixed thereto a piston 14 provided with a number of small perforations 15. 80 The valve stem has a roll 16 engaging a cam 17 on a shaft 18, which is eccentrically mounted with respect to the center line of the valve stem. A pin 19 on the valve cooperates with the bearing 9 to prevent the 85 valve from turning. The casing is provided with a removable cap 20 to permit assembling and inspection of the valve casing and parts. 90

Both valve casings are identical in construction, and a description of one is, therefore, sufficient. It will be seen that, if the shaft 18 is moved in a counterclockwise direction, Fig. 5, the valve will be raised from its seat against the pressure of the water 95 above the valve. If the shaft is now released, the pressure of the water will act to close the valve. With high pressure this is, however, liable to cause a water hammer; to 100

5 avoid this the piston 14 is provided, which, co-operating with the cylinder, acts as a retarding dash-pot to permit the valve to close gradually, thereby avoiding the water hammer.

10 Each shaft 18 has fixed thereto a handle 25, which in turn has pivoted thereto at 26 a toothed segment 27. The other end of the segment is connected by a link 28 with an arm 29 pivoted at 30 on the handle, and having a finger piece 31 integral therewith. A spring 32, between the handle 25 and the grip 31, normally operates to move the segment 27 outwardly, a lug 24 on the arm 29 15 engaging the handle 25 limiting the outward movement of the segment. Each valve operating shaft 18 is provided with a similar segment, and these segments are engaged by latches 33 pivoted at 34 and moved into engagement with the segments by means of a 20 spring 35. The tails 36 of the latches are engaged by the conical end of a plunger 37 working in a bearing 38 on the casing 3, and resting on the weighted end 39 of a lever 40 25 pivoted at 41 on a lug extending from the casing 3.

With this construction the right hand shaft 18, Fig. 2, may be moved in a counterclockwise direction to lift its valve, the teeth 30 on the segment 27 in such a case simply snapping over the beveled face of the right hand latch 33, and the segment and the shaft 18 will be retained in their position of adjustment. Similarly, the left hand valve 35 can be opened by moving its shaft 18 in a clockwise direction. In order to release a valve manually, the finger piece 31 is operated, which operates to withdraw its segment 27 out of engagement with its latch, 40 so as to permit manual return of the valve. Movement of the lever 40 in a counterclockwise direction, as by depression of the left hand end of the lever, will cause the pin 37 to rise, thereby spreading apart the tails of 45 the latches and bringing together the beveled ends so as to withdraw these beveled ends from the segments and release the same, thereby causing the water pressure to close the valves.

50 Mounted on a stand 45 is a casing 46 connected, at its lower end, by a pipe 47, with the interior of the tub or receptacle 1. Mounted on this casing is a cap 48, which has attached thereto, or is integral with, the 55 casing 3 supporting the valves and the mechanisms heretofore described. Movable in the casing is a carrier 49, which has mounted therein a vertical rod 50 connecting the bottom and top of the carrier. This rod has 60 slidably mounted thereon a sleeve 51 provided, at its lower end, with an annular shoulder 52, and at its upper end with a head 53. Slidable on the sleeve 51 is a weight or gravity member 530 forming an 65 actuator, as hereinafter described. This

weight has an annular shoulder 54 adapted to be engaged by a latch 55 pivoted at 56 on a lug 57 on the carrier 49. The latch has a tail 58 within the path of movement of a rod 59 guided in lugs 60 on the carrier, and connected, at its lower end, with a float 61 movable on the rod 50 and arrested by the cross piece 62 of the carrier.

70 Mounted on the head 48 is a bracket 65 carrying a casing 66, which is provided with a bearing 67 to receive a shaft 68. This shaft has fixed thereto a sheave 69 having attached thereto, at its periphery, a cord 70 passing through an aperture in the casing and over a pulley 71 mounted on a bracket 75 72 on the casing, over a second pulley 73 on the head 48, and hence connected to the upper cross piece of the frame 49. A spring 74 mounted on the shaft 68 between the casing and a knurled nut 75 on the shaft, operates to frictionally retain the shaft 68 and its sheave 69 in any desired adjusted position.

75 Loosely mounted on the hub of the sheave 69 is a second sheave 76, which has also attached to its periphery a cord 77 passing over a pulley 78 on the lever 40, over a second pulley 79 on the head 48, and hence connected, at its lower end, to the head 53 of the sleeve 51. The sheave 69 is provided 80 with a pair of spaced lugs 80, and the sheave 76 is provided with a lug 81. A spring 82 coiled between the sheaves, and engaging a pin 83 on the sheave 69 and a pin 84 on the sheave 76, normally operates to hold the lug 81 in engagement with the left hand lug 80, Fig. 4. The sheave 76 has fixed thereto a head 85, and this head is cut away, as shown at 86, to permit a limited movement of a pointer 87 fixed to the shaft 68 and moving 85 over a scale on a dial plate 88 attached to the casing by a ring 89. The space 86 is so proportioned as to leave ample clearance between the pointer 87 and the head 85, so that the relative movement of the sheaves 69 and 76 will only be limited by the lugs 80 and 81.

90 Assuming the parts to be in the position shown in the drawings, with the weight retained by the latch 55, with the valves set, and the segments latched in position by the latches 33, the operation will now be as follows:

95 The water in the tub rising will, after its level reaches a certain point, determined by the position of the float 61, raise this float, thereby causing the rod 59 to engage the tail of the latch 55 and release the weight or actuator 530. The weight will drop, and after falling a distance will be arrested by the shoulder 52. During this falling movement of the weight, it will acquire considerable inertia, and the sudden arresting of the weight will cause the inertia of the mass to pull on the cord 77. This cord is, however,

fixed to the sheave 76, which is in turn retained by the engagement of the lug 81 with the lug 80, it being understood that the tension of the spring 74 is sufficient to prevent movement of the shaft 68 under the pull exerted on the cord 77 by the weight. The result is, therefore, that the only thing which can give is the lever 40, and the left end thereof will, therefore, be pulled down, thereby causing the right end to raise and release the segments 27, as heretofore described, thereby causing the water pressure to close the valves. On account of the impact caused by the weight, and the accumulated inertia, the weight will act with considerable force, and with great rapidity, to release the valves quickly and with certainty.

In order to again set the apparatus, the operator will first turn the head 85 in a clockwise direction, thereby causing the sheave 76, through the cord 77, to raise the sleeve 51 carrying with it the weight 530 until the shoulder 54 snaps over the latch 55. The operator can readily determine when this takes place, for the reason that the pointer 87 will remain stationary until the lug 81 engages the right lug 80, Fig. 4, at which time the weight will have been raised. It is, of course, understood that the spring 82, being weaker in its action than 74, will, even when tensioned, not cause the shaft 68 to be moved. When the head 85 is now released, it will return back to normal position, and the sleeve 51 will, of course, drop.

The operator will then again set the valves as before, and the apparatus will then be in position for its next operation.

In the above adjustment, it has been assumed that the sheave 69 has not been moved, so that the apparatus is set for the same water level as before. In order to set the apparatus for a different water level, the operator will, when raising the weight, continue the movement of the handle until the pointer is moved to the proper position. This will raise the carrier 49 so as to raise the float and with it the latch 55 and all the other parts attached to the carrier, whereby the float will now be moved only at the high water level to release the controlling latch 55 for the actuator 530. If, on the other hand, the apparatus is to be set for a lower water level, then the operator can, either before or after raising the weight, move the head 85 in a counterclockwise direction, thereby adjusting the sheave 69 to lower the carrier.

It will, therefore, be seen that the invention accomplishes its objects. An apparatus is produced which is not alone simple in construction and operation, but entirely positive in its action. The use of springs, electro-magnets, and other devices inside of the

casing 46 is entirely eliminated, and there is only provided gravity means, which is positive in its action, and not liable to get out of repair. It will be noted that the lever 40, being weighted, and acting on the cord 77, will itself act to return the sheave 76 so that the spring 82 may be eliminated. The weight, possessing inertia, acts positively and quickly to instantly release the valves by a blow analogous to a hammer blow, whereby the weight can be made very small. The arrangement of the valve segments 27 is such that the valves may be readily set for any desired valve opening, and any desired quantity and temperature of water may, therefore, be obtained.

It is obvious that various changes may be made in the details of construction without departing from the spirit of this invention, and it is, therefore, to be understood that this invention is not to be limited to the specific construction shown and described.

Having thus described the invention, what is claimed is:

1. In fluid controlling mechanism of the class described, a fluid connection adapted to deliver the fluid to a receptacle, a valve in said connection, means for actuating said valve, means for setting said valve, a gravity member connected with said setting means for actuating the same, means for setting and retaining said gravity member in suspension with said valve set, and mechanical means governed by the rise of fluid in the receptacle for mechanically releasing said member, adapted to release said valve when the fluid in said receptacle reaches a predetermined maximum level.

2. In fluid controlling mechanism of the class described, a fluid connection adapted to deliver the fluid to a receptacle, a valve in said connection, means for actuating said valve, means for setting said valve, an operating connection for said setting means, a gravity member on said operating connection for actuating the same, means for holding said member in suspension, and mechanical means governed by the rise of fluid in the receptacle for mechanically releasing said member, constructed to cause said member to be arrested by said operating connection and act through inertia to release said valve when the fluid in said receptacle reaches a predetermined maximum level.

3. In fluid controlling mechanism of the class described, a fluid connection adapted to deliver the fluid to a receptacle, a valve in said connection, means for setting said valve, an operating connection for said setting means, a gravity member movable on said operating connection adapted to actuate the same, means for setting and retaining said member in suspension, and mechanical means governed by the rise of fluid in said receptacle for releasing said member, constructed

to cause said operating connection to arrest said member and operate to release the valve when the fluid in said receptacle reaches a predetermined maximum level.

5. In fluid controlling mechanism of the class described, a fluid connection adapted to deliver the fluid to a receptacle, a valve in said connection, means for setting said valve, an actuator for said setting means adapted 10 to actuate the same to release the valve, means for retaining said actuator in suspension, mechanical means governed by the rise of fluid in the receptacle for mechanically releasing said actuator to release said valve, 15 and means for adjusting said retaining means for a predetermined maximum level in the receptacle.

6. In fluid controlling mechanism of the class described, a fluid connection adapted to 20 deliver the fluid to a receptacle, a valve in said connection, means for setting said valve, an actuator for said setting means adapted to actuate the same to release the valve, means for retaining said actuator in suspension, 25 mechanical means governed by the rise of fluid in the receptacle for mechanically releasing said actuator to release said valve, and means for adjusting said retaining means for a predetermined maximum level in the 30 receptacle.

7. In fluid controlling mechanism of the class described, a fluid connection adapted to deliver the fluid to a receptacle, a valve in 35 said connection, means for setting said valve, an actuator for said setting means, means for retaining said actuator in position with the valve set, mechanical means governed by the rise of fluid in the receptacle for mechanically releasing said actuator to release 40 said valve when the fluid in said receptacle reaches a predetermined maximum level, and means for setting said actuator preparatory to its actuation for releasing the valve.

8. In fluid controlling mechanism of the class described, a fluid connection adapted to 45 deliver the fluid to a receptacle, a valve in said connection, means for setting said valve, an actuator for said setting means, means for retaining said actuator in position with the valve set, mechanical means governed by the 50 rise of fluid in the receptacle for mechanically releasing said actuator to release said valve when the fluid in said receptacle reaches a predetermined maximum level, and means for setting said actuator and its 55 releasing means preparatory to actuation for releasing the valve.

9. In fluid controlling mechanism of the class described, a fluid connection adapted to 60 deliver the fluid to a receptacle, a valve in said connection, means for setting said valve, an actuator for said setting means, means for retaining said actuator in position with the valve set, mechanical means governed by the 65 rise of fluid in the receptacle for mechani-

cally releasing said actuator to release said valve when the fluid in said receptacle reaches a predetermined maximum level, and means for adjustably setting said actuator and its releasing means preparatory to actuation for releasing the valve, adapted to cause release of said valve at a determined maximum fluid level in said receptacle. 70

9. In fluid controlling mechanism of the class described, a fluid connection adapted to 75 deliver the fluid to a receptacle, a valve in said connection, means for setting said valve, an actuator for said setting means, means for retaining said actuator in position with the valve set, mechanical means governed by 80 the rise of fluid in the receptacle for mechanically releasing said actuator to release said valve when the fluid in said receptacle reaches a predetermined maximum level, and means for setting said actuator and 85 thereafter its releasing means preparatory to actuation for releasing the valve.

10. In fluid controlling mechanism of the class described, a fluid connection adapted to deliver fluid to a receptacle, a valve in 90 said connection, means for setting said valve, an actuator for said setting means, means for retaining said actuator in position with the valve set, means governed by the rise of fluid in the receptacle for releasing said actuator to release said valve when the fluid in said receptacle reaches a predetermined maximum level, a carrier for said actuator and its retaining means, and means for adjusting said carrier for a determined 95 maximum fluid level in said receptacle. 100

11. In fluid controlling mechanism of the class described, a fluid connection adapted to deliver fluid to a receptacle, a valve in 105 said connection, means for setting said valve, an actuator for said setting means, means for retaining said actuator in position with the valves set, means governed by the fluid in the receptacle for releasing said actuator to release said valve, a carrier for 110 said retaining means and for its releasing means, and means for adjusting said carrier.

12. In fluid controlling mechanism of the class described, a fluid connection adapted to deliver fluid to a receptacle, a valve in 115 said connection, means for setting said valve, an actuator for said setting means, means for retaining said actuator in position with the valve set, means governed by the fluid in the receptacle for releasing said actuator to release said valve, a carrier for 120 said actuator, for said retaining means and for its releasing means, and means for setting said actuator.

13. In fluid controlling mechanism of the 125 class described, a fluid connection adapted to deliver fluid to a receptacle, a valve in said connection, means for setting said valve, an actuator for said setting means, means for retaining said actuator in position with the 130

valve set, means governed by the fluid in the receptacle for releasing said actuator to release said valve, a carrier for said actuator, for said retaining means and for its releasing means, and means for adjusting said carrier.

14. In fluid controlling mechanism of the class described, a fluid connection adapted to deliver fluid to a receptacle, a valve in said connection, means for setting said valve, an actuator for said setting means, means for retaining said actuator in position with the valve set, means governed by the fluid in the receptacle for releasing said actuator to release said valve, a carrier for said actuator, for said retaining means and for its releasing means, and means for adjusting said carrier and for setting said actuator.

15. In fluid controlling mechanism of the class described, a fluid connection adapted to deliver fluid to a receptacle, a valve in said connection, means for setting said valve, an actuator for said setting means, means for retaining said actuator in position with the valve set, means governed by the fluid in the receptacle for releasing said actuator to release said valve, a carrier for said actuator, for said retaining means and for its releasing means, and means for setting said actuator, and for thereafter adjusting said carrier.

16. In fluid controlling mechanism of the class described, a fluid connection adapted to deliver fluid to a receptacle, a valve in said connection, means for setting said valve, a carrier, an actuator for said setting means mounted on said carrier, a retainer mounted on said carrier for holding said actuator in position with the valve set, and a float adapted to engage said retainer to release said actuator.

17. In fluid controlling mechanism of the class described, a fluid connection adapted to deliver fluid to a receptacle, a valve in said connection, means for setting said valve, a carrier, an actuator for said setting means mounted on said carrier, a retainer mounted on said carrier for holding said actuator in position with the valve set, a float adapted to engage said retainer to release said actuator, and means for adjusting said carrier.

18. In fluid controlling mechanism of the class described, a fluid connection adapted to deliver fluid to a receptacle, a valve in said connection, means for setting said valve, a carrier, an actuator for said setting means mounted on said carrier, a retainer mounted on said carrier for holding said actuator in position with the valve set, and a float movably mounted on said carrier and adapted to release said actuator.

19. In fluid controlling mechanism of the class described, a fluid connection adapted to deliver fluid to a receptacle, a valve in

said connection, means for setting said valve, a carrier, an actuator for said setting means mounted on said carrier, a retainer mounted on said carrier for holding said actuator in position with the valve set, a float movably mounted on said carrier and adapted to release said actuator, and means for adjusting said carrier.

20. In fluid controlling mechanism of the class described, a fluid connection adapted to deliver fluid to a receptacle, a valve in said connection, means for setting said valve, a carrier, an actuator for said setting means mounted on said carrier, a retainer mounted on said carrier for holding said actuator in position with the valve set, a float adapted to engage said retainer to release said actuator, and means for setting said actuator and for thereafter adjusting said carrier.

21. In fluid controlling mechanism of the class described, a fluid connection adapted to deliver fluid to a receptacle, a valve in said connection, means for setting said valve, a carrier, a gravity actuator mounted on said carrier and connected with said setting means, a retainer mounted on said carrier for holding said actuator in position with the valve set, and a float adapted to engage said retainer to release said actuator.

22. In fluid controlling mechanism of the class described, a fluid connection adapted to deliver fluid to a receptacle, a valve in said connection, means for setting said valve, a carrier, an actuating connection for said setting means, a gravity actuator movable on said actuating connection, a retainer for said actuator mounted on said carrier adapted to hold the actuator in suspension, and a float adapted to engage said retainer to release said actuator, whereby said actuator will operate by its inertia to release said valve.

23. In fluid controlling mechanism of the class described, a fluid connection adapted to deliver fluid to a receptacle, a valve in said connection, means for setting said valve, a carrier, an actuating connection for said setting means, a gravity actuator movable on said actuating connection, a retainer for said actuator mounted on said carrier adapted to hold the actuator in suspension, means for setting said actuator, and a float adapted to engage said retainer to release said actuator, whereby said actuator will operate by its inertia to release said valve.

24. In fluid controlling mechanism of the class described, a fluid connection adapted to deliver fluid to a receptacle, a valve in said connection, means for setting said valve, a carrier, an actuating connection for said setting means, a gravity actuator movable on said actuating connection, a retainer for said actuator mounted on said carrier adapt-

ed to hold the actuator in suspension, means for adjusting said carrier, and a float adapted to engage said retainer to release said actuator, whereby said actuator will operate by its inertia to release said valve.

25. In fluid controlling mechanism of the class described, a fluid connection adapted to deliver fluid to a receptacle, a valve in said connection, means for setting said valve, 10 a carrier, an actuating connection for said setting means, a gravity actuator movable on said actuating connection, a retainer for said actuator mounted on said carrier adapted to hold the actuator in suspension, means 15 for setting said actuator and for thereafter adjusting said carrier, and a float adapted to engage said retainer to release said actu-

ator, whereby said actuator will operate by its inertia to release said valve.

26. In fluid controlling mechanism of the 20 class described, a fluid connection adapted to deliver fluid to a receptacle, a valve casing in said connection, a valve in said casing, a segment operatively connected with said valve, a latch engaging said segment adapted to adjustably set said valve, means for moving said segment into and out of engagement with said latch, and means governed by the fluid in the receptacle adapted to release said latch.

In testimony whereof I affix my signature this 26th day of April, 1916.

THEODORE BIRKENMAIER.
